UNITED STATES PATENT OFFICE

GEORGE ANDERSON, OF BATTLE CREEK, MICHIGAN

DESIGN FOR A MAGAZINE RACK

Application filed August 29, 1932. Serial No. 44,716. Term of patent 7 years.

To all whom it may concern:

Be it known that I, GEORGE ANDERSON, a citizen of the United States, residing at 169 West Michigan Avenue, Battle Creek, in the county of Calhoun and State of Michigan, have invented a new, original, and ornamental Design for a Magazine Rack, of which the following is a specification, reference being had to the accompanying drawing, forming part of this specification.

The figure is a perspective view of a magazine rack showing my new design.

The sides not shown are like the opposite sides shown.

I claim:

The ornamental design for a magazine rack as shown and described.

GEORGE ANDERSON.
